UNITED STATES PATENT OFFICE.

FREDERIC WILLIAM BARTHMAN, JR., OF BROOKLYN, NEW YORK.

DESIGN FOR A BOX.

SPECIFICATION forming part of Design No. 23,897, dated December 25, 1894.

Application filed October 23, 1894. Serial No. 526,763. Term of patent 14 years.

To all whom it may concern:

Be it known that I, FREDERIC WILLIAM BARTHMAN, Jr., a citizen of the United States, residing at Brooklyn, Kings county, State of New York, have invented and produced a new and original Design for a Box, of which the following is a description.

In the accompanying drawings forming part of this specification—Figure 1 is a perspective view of a box illustrating my design. Fig. 2 is a like view of the same, looking in another direction; and Fig. 3 is a longitudinal section of the same (on line 3—3 of Fig. 2) showing the cover removed.

15 The characteristic features of my design consist in a box having its cover and body of the formation of the crown and body of a cap of essentially the configuration and representation shown in the accompanying draw-

ings, and a closed bottom surrounded by a 20 groove.

In the drawings, A is a band extending almost the entire height of the box and forming the body thereof from the lower edge of which projects the peak-like ledge C.

25 B is the cover of the box having the form of the crown of a cap with a panel b, and ridges b'.

D is the bottom of the box surrounded by a groove d.

30 What I claim is—

The design for a box, substantially as shown and described.

FREDERIC WILLIAM BARTHMAN, JR.
